UNITED STATES PATENT OFFICE.

MILTON RUSLING WOOD, OF NEW YORK, N. Y.

ADVERTISING DEVICE.

Application filed November 4, 1920. Serial No. 421,670.

To all whom it may concern:

Be it known that I, MILTON RUSLING Wood, a citizen of the United States, residing at the city of New York, in the county 5 of New York, in the State of New York, have invented new and useful Improvements in Advertising Devices, of which the following is a specification.

My invention relates to that form of advertising device comprising an upright panel, cut out to receive a specimen of the article which is advertised on the panel.

The object of the invention is to provide a device of this kind so constructed that the 15 panel will be held upright at all times without depending solely upon the inserted specimen for its support.

To the above ends the present invention consists of an advertising device comprising 20 a base member, a panel extending upwardly therefrom, a cut out portion in the panel extending to the rear of the panel and forming an easel support adjacent to the opening formed by the cut out.

25 The invention is illustrated in the accompanying drawing, in which:

Figure 1, shows the device in perspective and showing a package inserted in the cut out.

30 Figure 2, shows a longitudinal sectional view taken through the panel and easel support, the package and the base portion being shown in plan.

Figure 3 is a vertical section taken through 35 the panel but showing the easel support and the package in elevation.

Similar reference characters will be employed throughout the specification and drawing to designate corresponding parts.

40 The device comprises a base portion 1, and a panel 2. These two parts are formed integrally of any suitable material, preferably of cardboard, of sufficient thickness to satisfy the requirements in such a device.

It will be noted that the upright panel 2 is considerably wider than the base 1 and they are united by a scored or other foldable joint 3, whereby they can be angularly disposed with relation to each other.

50 The upright panel 2 will be cut out as indicated at 4, to receive an article of mer-

chandise or a package, and of course, the opening will be approximately the size and shape of the article to be inserted therein at 55 any cross-section of said article.

The cut out 4 may be located at any point in the panel 2, but its base line 5 will be coincident with the foldable joint 3 between the panel 2 and the base 1. 60

In forming the cut out 4, the cut will be made along three lines only, that is to say, that portion of the panel cut out will be left attached to the panel 2 along a line 6, extending vertically, so that the portion that 65 is cut out may be extended rearwardly at an angle to the panel 2 forming an easel support 7, which supports the panel 2.

Assuming that the article to be displayed is a package of pancake flour 8, it is inserted 70 in the cut out 4, so that a portion of it extends forwardly and rearwardly of the panel 2; the forward portion resting upon the base 1, and the rear portion acting to hold the easel support 7 in an extended position. Of 75 course, any suitable advertising matter or decorative motifs may appear on the face of the panel.

With the package 8 in position in the cut-out of the panel, said package rests at the 80 front of the panel upon the flange forming the base 1 which base, it will be observed, is wholly at the front of the panel. It is to be noted further that at the back of the cut-out the panel is free from flanges and with 85 the cut-out made to produce the easel member 7 extending fully to the lower edge of the panel and to said front base flange 1. The arrangement permits of the easel member 7 contacting with the surface of the 90 table or the like while leaving the panel 2 at a very slight angle so that the package 8 is positioned substantially upright although the panel itself is tilted for the easel member 7 to constitute a firm prop. 95

Having described my invention, I claim:

An advertising device comprising a panel member and a base member united along a foldable line whereby the members may be disposed at an angle to each other in substantially vertical and horizontal planes respectively, the panel member being cut out upon three lines, one line being coincident with the foldable line uniting the two members, an-

other line being parallel therewith and at a distance therefrom corresponding to the height of the commercial package, and the other line joining the first two lines at one end, thus forming an opening to receive a commercial package of substantially the size and shape in cross section of said opening,

and a panel support connected by a vertically disposed foldable line along one of the vertical edges of the opening extending rearwardly from the back of the panel and held extended by contact with the commercial package when inserted in the opening.

MILTON RUSLING WOOD.
